ADDRESSING MACHINE

Harmon P. Elliott, Watertown, Mass.

Application July 2, 1941, Serial No. 400,770

11 Claims. (Cl. 101—48)

This invention relates to machines for printing and addressing public service and like bills and the invention is illustrated herein as embodied in a machine of the general type disclosed in United States Letters Patent No. 1,985,247 granted December 25, 1934, on an application filed in my name.

A public service bill, such for instance as a water bill, frequently consists of several connected sections. Each bill, as a whole, has the same printed matter but different bills have different addresses. The several connected sections of the same bill, however, are all provided with the same address. The various sections are used for different purposes. For example, in the bill which is a product of the illustrated machine, which has three sections, the left hand section is arranged to be cut off and mailed to the customer. The two remaining sections of the bill are retained at the office and are filed away. The middle section of the bill, which section contains substantially the same data as the left hand section, is severed from the right hand section and mailed to the customer whose bill has not been paid on or before a due date marked on the bill sections. The right hand section is retained in the office and is used for record purposes, a space being provided on this section of the bill in which payments made by the customer are recorded.

In order to save expense and also to insure that the bill will reach the customer promptly, these bill sections are of substantially the same size as a government postal card. Thus when these bills are to be sent to the customer without enclosing them in an envelope, it is desirable to address the back or under surface of the card to which a postage stamp may be affixed. It is essential, of course, that the address on the back of the section correspond to the address on the front of the card. This second addressing operation on the bill section is performed prior to printing the fixed data on the bill and from the same printing device which applied the addresses to the front side or surface of the bill sections.

One object of the present invention, accordingly, is to provide an addressing machine wherein the same address may be applied both to the front and rear surfaces of a bill. In accordance with this object, one feature of the invention resides in mechanism arranged to reverse the paper web between printing operations on one surface of the web and printing operations on the other surface of the web. In the

illustrated machine, the reversing operation is performed in such a manner that the address-printing devices are fed forwardly into and out of the addressing mechanisms in the same direction and in such a manner that substantially transverse registration of the addresses on the same section will be obtained. Such a construction constitutes a further object of the invention.

10 Another object of the invention is to improve generally upon the construction and operation of bill printing and addressing machines.

With the above and other objects and features in view, the invention will now be described with reference to the accompanying drawings in which:

Fig. 1 is a plan view of the right hand end or address-applying portion of a bill printing machine embodying the present invention;

20 Fig. 2 is a view in front elevation of the portion of the machine shown in Fig. 1;

Fig. 3 is a diagrammatic view of the bill-printing machine in which the present invention is embodied;

25 Fig. 4 is a view in cross-section taken along the line 4—4 of Fig. 1;

Fig. 5 is a detail plan view of the paper-strip take-up mechanism taken along the line 5—5 of Fig. 2;

30 Fig. 6 is a detail view of the bill-strip guide track at the strip-reversing part taken along the line 6—6 of Fig. 1;

Fig. 7 is a plan view of the front face of a bill which is the product of the machine; and

35 Fig. 8 is a plan view of the back face of the bill of Fig. 7.

The bill printing and addressing machine embodying the present invention comprises a flat horizontal table 10 which supports the operating parts of the machine and is supported by a frame 12. The machine is provided with a pair of reciprocating addressing mechanisms 14 and 16 operable in succession upon the same address-bearing printing device, herein a stencil, for applying the same address A on the two opposite faces of each of the several sections B, B', B'', of a bill C and operable upon different printing devices for applying different addresses on different bills. The machine is also provided with 40 perforating mechanism 18 for perforating or scoring certain bill sections transversely of their length along lines D so that coupons may be detached from the sections to accompany the payment for the bill.

50 The machine is also provided with feed con-

verting means 20 which converts the continuous movement of the web into intermittent movement in such manner that the web remains stationary at times during the operation of the addressing mechanisms 14 and 16 and in such position that the addresses are printed on different sections in accurate registration with printed data which is subsequently to be applied to the bill.

The means for printing the front face of the bills includes a front printing mechanism 22 which prints the common data E on the front face of the bill in register with the addresses thereon and also advances the web in a continuous manner. Back printing mechanism 24 is also provided which prints common data F on the back face of each bill. Severing mechanism 26 is also provided which severs the completed successive bills from the web or strip.

The various operative elements of the machine are driven by a power mechanism 28, Fig. 4 which is of a well-known type and is located in the base of the machine. The power mechanism 28 includes a continuously rotatable motor driven shaft 30, belt-driven from the motor 31, and a slower speed shaft 32, the rotation of which is controlled through suitable clutch controlled mechanism 34. The shaft 32 is positively connected through sprockets and a chain 36 with a short shaft 38 which is journaled beneath the table in a bracket 40. The shaft 38 is provided with a sprocket 42 which drives a sprocket 44 through a chain 46. The sprocket 44 is fixed to an operating and timing shaft 48 which is located at the rear of and above the table 10 and is journaled in lengthwise relation to the table in upstanding bearing brackets 50. The shaft 48 makes one complete revolution for each complete bill and operates all of the essential elements of the machine except the printing rolls and platens of the addressing mechanisms in timed relation with each other as will presently appear.

The shaft 38 has secured to its right hand end a sprocket 54 which drives, through a sprocket chain 56 and a sprocket 58 fixed to a horizontal shaft 60, cam means for reciprocating the platens and printing rolls of the addressing mechanism. The shaft 60 is journaled in depending brackets 62 carried by the lower surface of the table. The shaft 60 makes as many complete revolutions per bill as there are sections in the bill. The machine described herein is designed to make a bill having three sections. Thus, the shaft 60 makes three complete revolutions per bill.

The paper from which the bills are made is in the form of a web 64 contained in a roll 66 which is located adjacent to the right hand end of the table 10 and is supported in suitable brackets (not shown). The roll is prevented from unrolling at a greater rate than the paper is withdrawn therefrom by any suitable brake or other friction means (not shown). The paper web is withdrawn from the roll in a continuous manner and at a rate which is slightly although definitely, greater than the rate of advance of the web through the printing mechanism so that the web forms a loop 68, from which loop the web is drawn by the web advancing mechanism without effort.

The web passes over a guide bar 67, Figs. 2 and 5, fixed to the lower end portions of supporting straps 69 suitably received to the bottom face of the table 10. The web withdrawing or take-up mechanism comprises a driving or feed roll 70

fixed on a shaft 71 journaled in bearings formed in the lower end portion of brackets 73 fixed to the machine bed 10 which shaft is connected through miter gears 72 with a shaft 74 journaled in a bracket 75 and positively driven from the right hand end of the shaft 60 by a sprocket 76 which drives a sprocket 78 fixed to the left hand end of the shaft 74 through a sprocket chain 80. The paper web is pressed onto the periphery of the feed roll by an idler roll 82 which is carried at the ends of arms 84 pivoted on a shaft 86 journaled in right hand extensions of the brackets 73. A lever 88 is pivoted concentrically with the roll 70 and has a pin 90 which, when the lever 88 is moved to the right as shown in Fig. 2, raises the arms 84 and thereby raises the roll 82, thus arresting the driving of the web 64. The free end of the lever 88 is located above the table within convenient reach of the operator who is intended to operate the lever and thus momentarily arrest the feeding of the web when the loop 68 becomes too long.

The web 64 passes upwardly from the loop 68 and over the vertical wall of a web guide 92. An electric contact member 94 rides on the web and, upon breakage of the web, will make contact with the wall of the guideway thereby completing an electric circuit which not only sounds an alarm but also stops the machine in a manner not herein essential to explain.

An idler roll 96 is mounted in downwardly depending brackets 98 fixed to the under surface of the table 10. The web passes upwardly from the guide 92 to the guide roller 96 and thence horizontally from one end to the other of the machine and in succession to the various operating and printing mechanisms. The position of the web 64 with respect to the operating mechanisms is determined by a plurality of web guides or tracks 102 (see especially Figs. 1 and 4), disposed on opposite sides and along the length of the web. The web guides are, in general, similarly constructed and have vertical plates 103 formed with laterally extending ears 104 having elongated slots through which screws 106 pass for securing the web guides in suitably adjusted and aligned positions transversely of the table 10.

The addressing mechanism which includes the addressing heads 14 and 16 includes also a stencil holder 108 which contains a vertical stack of stencils, 109 the successive lowermost ones of which are moved out of the holder in successive order by a pusher member 110 and into and advanced in step by step manner along a pair of parallel stencil tracks or guideways 112 which are suitably secured in position above the web guides 100 and 102. The stencils are delivered from the printing positions into a stencil elevating mechanism 114 of the general type disclosed in United States Letters Patent No. 1,210,440, granted January 2, 1917, on an application filed in the name of Sterling Elliott. The elevating mechanism delivers stencils in successive order from the tracks 112 into the bottom of a stencil receiver 116.

The pusher 110 is reciprocated through a link 111 pivoted to the front end of a lever 113 pivoted intermediate its ends on a vertical stud 115 fixed to the table. The rear end of the lever has an upstanding cam follower 117 located in the cam groove 119 of a cam 121 fixed to the operating shaft 48. The arrangement is such that one stencil is advanced for each complete rotation of the shaft 48.

The addressing mechanisms 14 and 16 are of

usual and identical construction and are timed to operate simultaneously. It will be necessary, therefore, to describe only one of these mechanisms in detail. Each addressing mechanism includes an ink printing or impression roll 118 which is provided with ink by suitable inking mechanism. The printing roll 118 is located above the stencil track and journalled in the forward end portions of arms 120 forming a part of a frame 122 pivotally supported by a shaft 124 carried by a bracket 125. Each roll 118 is provided with a cooperating platen 126 which is located beneath the web 64 at the forward ends of arms 128 pivoted at 129 to the bracket 125. The platen is reciprocated toward and away from the stencil tracks by means including a lever 130 which is pivoted on a shaft 132 carried by the bracket 125 and has an upwardly directed extension provided with a cam face 134 which is adapted to engage a cam roller 135 of and to raise and lower the platen. The lever 130 is connected by a pivoted link 136 with a downwardly extending arm 138 of the printing roll supporting frame so that the reciprocation of the lever 130 causes the platen 126 and the roll 118 to move toward and away from each other.

The lever 130 is reciprocated by an eccentric 140 which is fixed to the shaft 60 and is encircled by an eccentric strap 142 which is pivotally connected with the lower end of the lever 130. Thus the printing roll 118 and the platen 126 of the addressing mechanism 18 perform one complete operation for each complete rotation of the shaft 60 and thus print the address of the stencil contained in the stencil track upon the front face of the web.

The web is advanced following each addressing operation. The same stencil, however, remains in position until as many addressing operations have been made thereon as there are sections in the bill. For a three-section bill, as here shown, there will be three addressing operations.

As hereinbefore stated, the addressing mechanism 16 operates simultaneously with the addressing mechanism 14. The addressing mechanism 16, however, prints the address of a stencil contained in a stencil track upon the back face of the web. The web is advanced following each addressing operation of the addressing mechanism 14 and passes through an inverting or reversing mechanism 144 before the same section of the web reaches the address printing mechanism 16.

As shown most clearly in Figs. 2, 3, and 6, the web 64 passes beneath and through the addressing mechanism 14 and thence over a roll 146 and downwardly and under a web-inverting roll 148 which is mounted for rotation at an angle of substantially 45° to the path of movement of the web 64. The roll 148 is rotatably mounted in bearing blocks 150 that are vertically adjustable in an upstanding U-shaped bracket 152 which is suitably secured to the base 12 of the machine. The bracket 152 is provided with vertical slots 154 for receiving bolts 156 fixed to the bearing blocks 150. The paper web passes upwardly from the roll 148 over a guide roll 158 and thence between the web guide members 120. It is to be noted that the table 10 of the machine is cut away, as illustrated in Fig. 6, to receive a plate 160 to the lower surface of which the rolls 146 and 158 are rotatably mounted in suitable bearings. The paper web 64 is threaded under the roll 148 so that the bottom surface of the web 64 in the downward pass of the web is visible from

the front of the machine. Thus in the upward pass of the web, the top surface of the web is exposed to view and the top surface which is exposed to view in the upward pass of the web is 5 in contact with the guide roll 158 and thus the surfaces of the web are inverted or reversed by means of the reversing mechanism 144 and what was originally the bottom surface of the web is now the upper surface which is to be exposed to 10 the action of the addressing mechanism 16.

The distance, measured along the length of the paper web, between the two addressing mechanisms 14 and 16 plus the loop formed by the reversing roll 148 is equal to three bill lengths, 15 for the particular machine herein illustrated. The center line distance between the two addressing mechanisms 14 and 16 along the stencil track is equal to the length of three stencils. Thus, when three addresses have been applied to the web 64 from one stencil that stencil is fed out of position below the addressing mechanism 14 and the portion of the web which is addressed is moved step-by-step from below the addressing mechanism 14. The next successive stencil then 20 has three addressing operations performed thereon and then that stencil is fed out of position below the addressing mechanism 14. The same number of operations are performed on the next two succeeding stencils. The stencil which was first in addressing position below the addressing mechanism 14 has now been moved into addressing position below the addressing mechanism 16. At the same time, of course, the web 64 has been fed forwardly and the web inverted or reversed so that the portion of the web which 25 received the first address from the first stencil is located below the addressing mechanism 16. Thus, the addressing mechanism 16 will perform three addressing operations upon the backface of the web 64 and then that stencil will be fed out of addressing position and into the stencil receiving holder 116, as hereinbefore described. By this means, the front and rear or top and bottom surfaces of the web 64 are provided with 30 the same addresses which are in transverse alignment with each other and in the same bill section.

Successive addressing operations are performed on successive stencils; and the web 64 35 after having been addressed on both sides passes from the second addressing mechanism 16 to the scoring mechanism 18. This mechanism includes an arm 162, Fig. 3, which is pivoted intermediate its ends to a bracket 164 fixed to the top surface of the table 10 and at its forward end carries a perforating or scoring knife 166. The rear end of the arm 162 is provided with a cam roll 168 which engages a cam disc 170 fixed to the shaft 48. The cam disc 170 has two notches 171 therein into which the cam roll falls to permit the arm 162 to be dropped to cause the perforating knife 166 to score the paper. The particular bill which is the product of the present invention is scored in two places and hence 45 the scoring mechanism operates twice on each bill, first to form the left hand scoring line D and second to form the right hand score line D. It is apparent, however, that there can be as many notches in the cam disc 170 as there are lines of scoring for each bill and that the notches will be peripherally spaced in proportion to the lengths of the sections between the score lines.

The web is advanced from the scoring mechanism through the feed converting mechanism 20 50 and thence to the front printing mechanism 22

which prints the data E, Fig. 7, common to all the bills on the front faces thereof in registration with the addresses. This front printing mechanism includes front printing impression and platen rolls 172, 174 which are mounted for joint rotation. The web is advanced continuously by the rolls 172 and 174 at such a rate that one bill length passes from the front printing mechanism and the addressing mechanism 16 at the same time. Since, however, the addressing mechanism has reciprocating elements which necessitate the web being stationary at the times that the addressing operation is performed and since the sections B of each bill are or may be of unequal length the feed converting mechanism herein provided converts the continuous advance of the web 64 under the action of a front printing mechanism 22 into an intermittent advance by steps of suitable length so that the addresses and the printing data on all the bills will be in constant registration with each other.

The feed converting mechanism 20 is substantially the same as that described in detail in my above mentioned Letters Patent No. 1,985,247 to which reference may be made for a more detailed description of the construction and operation of this mechanism. The mechanism comprises, as shown diagrammatically in Fig. 3, a vertically reciprocating roll 176 located under the paper web which is held down on opposite sides of the roll by guide rolls 177, said feed converting roll is arranged to be moved upwardly predetermined distances at predetermined intervals by a multi-lobed cam 178 fixed to the forward end of a substantially horizontal shaft 180 driven by miter gears 179 from the shaft 48, the cam operating on the swinging frame 18 in which the roll 176 is rotatable. The cam 178 is provided with as many repetitions or lobes as there are address sections of the bill. Since the present machine is designed to make three section bills, the cam 178 is illustrated herein as provided with three lobes 182. The shape of the cam is such that the roll 176 is elevated so as to deflect the web 64 laterally of its length between the guide rolls 177 and to alter the length of the path of travel of the web and thereby to draw such amount of paper through the addressing mechanism which added to the amount advanced by the front bill mechanism 22 during such movements is the requisite amount of paper advance through the addressing mechanism for a bill section. The roll 176 is then dropped, leaving a loop of paper which the printing rolls must exhaust before they can advance the web in the addressing mechanisms. Thus, the web is stationary at times in the addressing mechanisms and during the operation thereof. The amount of draw or lift of each of the cam lobes 182 may be different for bill sections of different lengths and consequently may be so arranged that the roll 176 is operated to draw a greater amount of paper past the addressing mechanisms 14 and 16 for a long bill section than for a short bill section. Thus, while the front printing mechanism 22 operates to advance the web 64 through the printing mechanism in a continuous manner, the movement of the web is converted into an intermittent advance by a converting mechanism 20 so that the web is advanced past the addressing mechanism by steps which may vary in length depending upon the length of the bill sections and the web, of course, is held stationary momentarily to permit the ad-

ressing mechanisms 14 and 16 to perform addressing operations on successive bill sections.

The addressing mechanisms 14 and 16 which as hereinbefore stated are substantially identical and are provided with inking mechanisms 186, Fig. 4, which are arranged to supply ink to the printing roll 118. The inking mechanisms 186 can be of any suitable type and need not be further described herein except to state that each includes a roll driving shaft 188 which is common to both mechanisms and is driven, Figs. 2 and 4, through a belt 192 by the shaft 194, which shaft is driven by a belt 195 from the continuously rotating shaft 30 of the power mechanism 28. The mechanism for supplying ink to front and rear printing mechanisms 22 and 24 is not described herein, since it is of substantially the same type as that disclosed in my above mentioned Letters Patent No. 1,985,247.

The front and back addressed and front printed web passes from the front printing mechanism to the back printing mechanism 24 where it receives the printed data H, Fig. 8, common to all bills and herein common to the first two of the three sections of each bill but omitted from the last or office section. The back printing mechanism is similar to the front printing mechanism except that the positions of the impression and platen rolls are reversed, the impression roll being beneath the web. The rolls of both printing mechanisms have equal diameters and are driven at the same speed from the shaft 48.

After the web has passed through the front and rear printing mechanisms 22 and 24 and has been completely printed and addressed, it passes through the severing mechanism 26 which operates in the usual manner to sever the successive bills from the web 64, the reciprocating shearing lever 196 of the shearing mechanism being operated by the single lobe cam 198 of the shaft 48 once for each complete rotation of the shaft.

After the bills have been completely printed and addressed on both sides, and severed from the web as above described, the severed bills C are sent to the bookkeeping department where the various blanks on the face of the bill are filled in with data indicating, for example, the number of cubic feet or gallons of water used, the amount of the bill and the date which the bill is due. After the various item spaces have been filled in, the left hand section of the bill will be cut off along the line K-K. This portion which is substantially the same size as a Government postal card has a postage stamp L applied thereto and is mailed to the customer. The remaining two sections of the bill are filed away in the office until such time as the bill is paid or the due date of the bill has arrived. If, on the due date, the bill has not been paid by the customer, the remaining two sections of the bill will be severed along the line M-M and a stamp L' will be applied to the central section and sent to the customer to remind him that the bill has not been paid. The right hand end or office section of the bill is then filed away until the bill is paid or until the time arrives when the following month's bills are to be prepared and sent to the customer.

The narrow sections to the right of the score lines D of the left hand and central bill sections are intended to be severed from the body of the sections and presented as coupons with payment of the bill. It is apparent that the machine dis-

closed herein produces a multi-section bill which is arranged to facilitate bookkeeping procedure and to provide a method for filing the bills to provide a constant check upon the bills payable to ascertain whether or not all of the bills are paid upon the due date.

Having thus described my invention, what I claim as new and desire to secure by Letters Patent of the United States is:

1. In an addressing machine, addressing mechanisms, means for presenting successive address-bearing printing devices in succession first to the action of one and thence to the action of the other of said mechanisms, means for advancing successive bills in succession from one to the other mechanism, means for inverting the successive bills after they have been acted on by one addressing mechanism and before they are acted on by the other addressing mechanism whereby both opposite faces of the bills receive addresses, and means for operating the aforesaid means to provide the same address on both faces of any one bill and different addresses on different bills.

2. In an addressing machine, means for advancing a succession of addressing devices, means for effecting a plurality of addressing impressions on a single device at each of a plurality of locations, means for advancing the same bill form step by step to the action of the same device at each of said plurality of locations, means for reversing the form between addressing locations whereby to apply the same address to opposite faces of the bill form, and means for presenting different addressing devices to action on different bill forms.

3. In an addressing machine, two printing mechanisms, means for advancing a succession of addressing devices to the action of first one and then the other mechanism, means for advancing a bill form to the action of first one and then the other mechanism in timed relation to the advance of an addressing device from one to the other printing mechanisms to receive an impression of the same addressing device in both printing mechanisms, and means for reversing the bill form between said mechanisms.

4. In an addressing machine, two printing mechanisms, means for presenting the same bill form in succession to both mechanisms, means for presenting the same addressing device in succession to both mechanisms, and means for presenting one face of the bill form to the action of the addressing device at one printing mechanism and for presenting the opposite face of the same bill form to the action of the same addressing device at the other printing mechanism.

5. In an addressing machine, two addressing mechanisms, means for advancing a succession of address devices first to the action of one and then to the action of the other mechanism, means for advancing successive bill forms first to the action of one and then to the action of the other mechanism, and means for presenting different faces of a bill form to the same address device in the two mechanisms.

6. In an addressing machine, two address applying mechanisms, a guideway for guiding address devices from one to the other mechanism, means for guiding successive bill forms from one to the other mechanism, means for operating said mechanisms, means for advancing address devices along said guideway first into one and

thence into the other mechanism intermittently to change devices in said mechanisms only following a predetermined plurality of operations of said mechanisms thereon, means for advancing a bill form intermittently through each of said mechanisms one step following each operation thereof on the same address device and for presenting a different bill form and a different device to the mechanisms, and means for reversing the bill forms in their travel from one to the other mechanism to present one face to the action of one mechanism and device and the opposite face to the action of the other mechanism and the same device whereby the same address is applied in different parts of the same bill form and also on opposite sides thereof.

7. In a bill printing and addressing machine, a first addressing mechanism including means successively operatively engageable with a bill for printing repetitions of the same address on different sections of one surface of the bill, a second addressing mechanism including means successively engageable with the bill for printing repetitions of the same address as said first addressing mechanism on the different sections of the other surface of the same bill, means for presenting a succession of addressing devices first to the action of one addressing mechanism and thence to the action of the other mechanism, means for step by step feed of the bill to and through both addressing mechanisms, and means for reversing the bill between addressing operations of said two addressing mechanisms on the different surfaces of the bill.

8. A bill addressing machine having means for feeding a continuous bill web through the machine, addressing mechanism for printing repetitions of the same address on a plurality of different sections on one surface of the bill web, mechanism for reversing the bill web after the web has passed through the addressing mechanism, and a second addressing mechanism located a predetermined number of bill lengths of web travel from the first addressing mechanism for applying repetitions of the same address to the other surface of the same sections to which the addresses were applied by the first printing mechanism, and means for advancing a succession of address-bearing printing devices from one addressing mechanism to the other addressing mechanism in succession to present the same printing device to the same bill of the web in both addressing mechanisms.

9. A bill addressing machine having means for feeding a continuous bill web through the machine, a holder for a stack of printing devices, means for moving the printing devices out of the holder and step-by-step into successive address printing positions, addressing mechanism located in one printing position for printing repetitions of the same address on a plurality of sections on one surface of the bill web forming a bill length, mechanism for reversing the bill web after the bill web has passed through the addressing mechanism, and a second addressing mechanism located in another printing position in alignment with the first addressing mechanism a predetermined number of bill lengths of web travel from the first addressing mechanism for applying repetitions of the same address to the other surface of the same sections to which the addresses were applied by the first addressing mechanism.

10. In a bill printing and addressing machine,

in combination, two addressing mechanisms, means for advancing a succession of printing devices to the action of one addressing mechanism and thence to the action of the other addressing mechanism, means for advancing a succession of bills to the action of one addressing mechanism and thence to the action of the other addressing mechanism, means for operating said printing device advancing means and said bill advancing means to cause each addressing mechanism to impress repetitions of the address of the same printing device on different sections of a bill and repetitions of the addresses of different printing devices on different bills, and means for reversing the bills between addressing mechanisms whereby to provide the bill with repetitions of the same address on opposite sides of the bill.

11. In an addressing machine, two printing

mechanisms, means for feeding a succession of bills and a succession of printing devices to one of the printing mechanisms with one face of each bill at said printing mechanism in coacting relation with a different printing device, means for feeding the succession of bills and the succession of printing devices thence to the other printing mechanism with the opposite face of each bill at the second printing mechanism in coacting relation with the same printing device with which that bill coacted in the first printing mechanism, and means for operating the two said printing mechanisms to provide printing impressions from the same printing device on opposite faces of the same bill and printing impressions from a different printing device on the opposite faces of each different bill.

HARMON P. ELLIOTT.
